UNITED STATES PATENT OFFICE

JOHN W. MANSFIELD, OF DETROIT, MICHIGAN

STRAIGHT-PIN PINNING ATTACHMENT FOR PRESSES

Application filed May 20, 1930. Serial No. 454,165.

This invention relates to improvements in pin inserters, particularly a press for inserting straight pins into bodies of various types.

The primary object of the present invention is to provide an automatic pin feeding mechanism carried by a presser member whereby a single pin will be discharged each time the presser member is lowered into contact with a base block.

10 Another object of the invention is to provide a pin feeding mechanism which will discharge only a single pin at a time through the under face of a presser block and which is so associated with the presser block that the 15 latter may be lowered for operation upon a body for the purpose of pressing a discharged pin thereinto without effecting the pin discharge mechanism.

The invention will be best understood from 20 a consideration of the following detailed description taken in connection with the accompanying drawings forming part of this specification, with the understanding, however, that the invention is not confined to any strict 25 conformity with the showing of the drawings but may be changed or modified so long as such changes or modifications mark no material departure from the salient features of the invention as expressed in the appended 30 claims.

In the drawings:

Figure 1 is a view in side elevation of an arbor press showing the application of the present invention thereto.

35 Figure 2 is an enlarged detailed view partly in elevation and partly in section of the attachment illustrating the operation thereof.

Figure 3 is an enlarged sectional view of the lower portion of the attachment showing 40 the method of releasing a pin.

Figure 4 is a horizontal sectional view through the casing of the pin holding bar and the associated elements.

45 Figure 5 is a view of a base block in which a pin receiving bore has been formed at an angle other than a ninety degree angle to the work.

In the drawings the straight pin pinner embodying the present invention is shown as applied to an arbor press which is indicated gen-

erally by the numeral 1. This press has the arbor portion 2 through which there works in a vertical plane a rack 3 operated by a pinion 4 to the shaft of which the arms 5 are attached.

55 On the base 6 of the press is mounted a base block 7 which is disposed directly beneath the rack 3 and attached to the lower end of this rack is a presser block 8 which may be moved down into contact with the 60 base block for effecting a pressing operation. In the present invention the presser block 8 is provided in its rear face with the inwardly and downwardly directed bore 9 which, adjacent its lower end, communicates with a 65 straight downwardly directed bore or passage 10 which opens through the bottom of the presser block and which has opening 70 thereinto from the rear face of the presser block the inwardly directed passage 11, the 70 outer end of which is of enlarged diameter and threaded as indicated at 12.

The base block 7 is provided with a pin receiving recess 13 with which the pin discharging passage 10 of the presser block 75 comes into alignment when the presser block is lowered.

Threaded into the outer portion of the rearwardly directed passage 11 in the presser block and extending rearwardly from the 80 presser block at right angles to the face thereof is a cylinder 14, the outer end of which is closed by a cap 15 which maintains in place within the cylinder a coil spring 16. Extending longitudinally through the spring 16 and 85 through the cylinder 14 is a pin retaining bar 17 the inner end of which normally extends into the passage 10 under the influence of the spring 16, the inner end of which bears against a transverse stop 18 carried by the 90 pin holding bar 17. The outer end of the bar 17 passes through the cap 15 and is pivotally secured in the bifurcated leg 19 carrying the base block contacting foot 20.

This foot 20 has its under surface rounded 95 as indicated at 21 so that when the presser block 8 is brought down onto the working surface of the base block 7 the rounded portion of the foot 20 which projects a slight distance below the bottom face of the presser 100

block 8 will be brought into contact with the base block and will slide thereon so that the leg 19 will be caused to shift into an angular position from the vertical fulcrum at its 5 upper end against the cap 15 and thus pulling out the bar 17 against the tension of the spring 16.

Extending down into the passage 9 is a pin delivering tube 22, the upper end of which 10 carries and has discharging therewith a hopper or funnel 23 in which a number of pins are placed when the machine to which the device is applied is in operation.

The presser block 8 is preferably pivotally 15 connected to the operating rack or bar 3 to which it is attached so that a slight amount of flexibility is permitted to compensate for any unevenness which may exist between the opposing faces of the presser block and base 20 block and the faces of a body interposed therebetween and into which a pin is to be pressed.

In the operation of the present machine the operating handle or arm 5 is manipulated so that the bar 3 and the mechanism carried 25 thereby will be raised, during which operation a stop member, such for example as the pin 24, will be brought into contact with the upper part of the arbor to jar the hopper 23 and thus cause a number of the pins 25 to be 30 fed into the tube 22.

The presser block will then be lowered until it is brought into contact with the base block 7 at which time the foot 29 will be oscillated as previously described retracting the bar 17 35 and allowing one of the pins 25 to pass down through the discharge passage 10 and into the recess 13 in the base block. The presser block is then again raised and the piece of work into which the pin is to be pressed, such 40 for example as the washer 26 in which a suitable pin receiving aperture 27 has been formed, is then placed into position on the base block 7 with the aperture 27 in position to receive the pin 25 standing upright in the 45 recess in the base block, after which the presser block is again lowered until it comes into contact with the washer which it forces down onto the base block carried pin forcing this pin into the aperture 27. It will, of 50 course, be understood that due to the interpositioning of the washer 26 between the base block and the presser block the foot 20 will be prevented from coming into contact with the base block and therefore no pin will be 55 discharged during this operation.

After one of the pins 25 has been discharged into the base block receiving recess 13 in the manner above described, as soon as the presser block 8 is lifted from contact with the base block the spring 16 will move the bar 17 inwardly against the next pin 25 which has already moved partly past the passage 11 and will hold this pin against further movement 60 until the pressing operation described has

been completed and the presser block again lowered onto the base block.

While I have particularly described the application of a pin to a washer or other body, in a position at right angles to the surface of the body, it is, of course, to be understood that I do not wish to be limited in this manner for this device may also be employed for inserting pins into bodies at angles other than at right angles. For example, 70 in Figure 5 there is illustrated a base block indicated by the numeral 7' upon which is shown a washer 26'. This washer has an aperture 27' formed therethrough at an oblique angle with respect to the surface of 75 the washer as shown. In order to insert the pin into an aperture disposed at an angle like this it is necessary that the block 7' have the aperture 13' which is formed therein arranged at the same angle with respect to the 80 top surface thereof as the angle 27' is arranged with respect to the surface of the washer 26'. This is the only change necessary in the construction of the device to enable one to insert pins at any angle desired. 85 In other words, the base block must have the pin receiving aperture or bore disposed at the same angle as the passage in the body into which the pin is to be pressed.

While I have particularly described the 90 present invention as being applicable to an arbor press it is, of course, to be understood that I do not wish to be limited in any manner in this respect for it will be readily obvious to those familiar with the art to which 95 this invention relates that the device may be readily used in association with other types of machines such for example as drill presses, punch presses or the like.

Having thus described my invention, what 105 I claim is:

1. In a machine of the character described having a base block and a vertically reciprocable element thereover and movable relative thereto, a presser block carried by the reciprocable element and having a downwardly opening passage therethrough, means for supplying pins to said passage for discharge therethrough into a receiving recess in the base block, and a pin retaining member 110 adapted to be tripped upon bringing the presser block into contact with the base block for the release of a pin for discharge into the base block recess.

2. In a machine having a base block and a reciprocal presser element movable relative thereto, said presser element having a passage therethrough opening downwardly towards the base block and the base block having a recess in alignment with said passage, a pin 120 feeding member arranged to discharge pins into said passage, a laterally movable pin retainer carried by the presser block and extensible into the pin receiving passage to normally prevent the passage of a pin there- 125

- through, and a spring controlled oscillatable member carried by the pin retainer, said oscillatable member contacting with the base block upon the lowering of the presser block 5 thereagainst to retract the pin retainer for the discharge of a pin into said recess.
3. The combination with a press having a base block and a reciprocable member movable relative thereto, a presser block carried 10 by said member and having a passage therethrough opening through the lower face thereof in alignment with an upwardly opening recess in the base block, a pin hopper, a conveyor leading pins from said hopper into 15 said presser block passage, a laterally shiftable bar carried by the presser block and having one end extensible into said passage to control the movement of pins therethrough, resilient means normally urging said bar inwardly, and a trip element oscillatably carried by the bar and adapted when brought 20 into contact with the base block to retract the bar against the action of the resilient element to permit the passage of a pin to the 25 base block recess.
4. The combination with a press having a base block and a reciprocable member movable relative thereto, a presser block carried by said member and having a passage there- 30 through opening through the lower face thereof in alignment with an upwardly opening recess in the base block, a pin hopper, a conveyor leading pins from said hopper into said presser block passage, a laterally shift- 35 able bar carried by the presser block and having one end extensible into said passage to control the movement of pins therethrough, resilient means normally urging said bar inwardly, and a bar actuating foot pivotally 40 mounted upon the outer end of the bar having a rounded lower surface arranged to be brought into contact with the top of the base block when the presser block is lowered thereagainst to retract the pin retaining bar for 45 the discharge of a pin into the recess.
5. The combination with a press having a base block and a reciprocable member movable relative thereto, a presser block carried by said member and having a passage there- 50 through opening through the lower face thereof in alignment with an upwardly opening recess in the base block, a pin hopper, a conveyor leading pins from said hopper into said presser block passage, a laterally shift- 55 able bar carried by the presser block and having one end extensible into said passage to control the movement of pins therethrough, resilient means normally urging said bar inwardly, a sleeve carried by the presser block 60 and having said bar passed therethrough and further housing said resilient element, and a presser foot having an upstanding leg portion pivotally attached to the outer end of said bar and having a rounded lower portion 65 disposed in a plane below the presser block
- for contact with the top of the base block when the presser block is lowered thereagainst, said foot being oscillated and fulcruming the leg against said sleeve to retract the bar for the passage of a pin into the base 70 block recess.
- In testimony whereof I hereunto affix my signature.
- JOHN W. MANSFIELD.
